UNITED STATES PATENT OFFICE.

JONATHAN A. HUNT, OF WESTBOROUGH, MASSACHUSETTS.

DESIGN FOR A BICYCLE-SADDLE.

SPECIFICATION forming part of Design No. 28,822, dated June 7, 1898.

Application filed April 8, 1898. Serial No. 676,963. Term of patent 14 years.

To all whom it may concern:

Be it known that I, JONATHAN A. HUNT, a citizen of the United States, residing at Westborough, in the county of Worcester and State of Massachusetts, have invented and produced a new and original Design for Bicycle-Saddles, of which the following is a specification, reference being had to the accompanying drawings, forming a part thereof.

My invention relates to a bicycle-saddle; and it consists in a new and original design for a bicycle-saddle, as will be hereinafter fully described.

Referring to the drawings, Figure 1 is a plan view of a bicycle-saddle, showing my design. Fig. 2 is a front or rear view; and Fig. 3 is a cross-section on line 3 3, Fig. 1.

The leading feature of my design for a bicycle-saddle consists in the shape or configuration of the base or lower part of the saddle and of the seat or top elevated above the base. The base or lower part of the saddle has an outline of substantially elliptical shape in plan view, without the usual forward extension or pommel portion. The seat or top of the saddle is elevated above the base and substantially covers it. The seat or top is narrower at its central portion and also depressed in line with the central front and rear depressions in the base to give the appearance

of two pads or cushions united at their inner edges.

In the accompanying drawings, 1 is the base or lower part of a bicycle-saddle embodying my design. The base 1 is of substantially 35 elliptical shape in plan view. The sharper curves *a a* of the ellipse are the side edges of the saddle and the other curves *b c* the front and rear edges of the saddle, respectively.

The seat or top 2 of the saddle of my design 40 substantially covers the base 1 and is elevated above the same. The outline of the seat or top 2 corresponds with the outline of the base 1, except at the central portion of the seat, where there is a recess at the front and rear 45 portion, making the seat narrower at its central part. (See Fig. 1.) The top surface of the seat 2 is depressed at its narrow part to extend in a lower plane than the rest of the seat and gives to the seat the appearance of 50 two pads united at their inner edges in the plan view of the saddle, Fig. 1, and also in the front or rear edge view, Fig. 2.

What I claim is—

The design for a bicycle-saddle substantially as shown and described.

J. A. HUNT.
